DESIGN FOR A DISPLAY DEVICE

Charles T. Andrews, Toronto, Ontario, Canada,
assignor to Multiple Displays, Inc., New York,
N. Y., a corporation of New York

Application December 4, 1945, Serial No. 124,338

Term of patent 3½ years

(Cl. D80—9)

To all whom it may concern:

Be it known that I, Charles T. Andrews, a citizen of the Dominion of Canada, residing at Toronto, Province of Ontario, Dominion of Canada, have invented a new, original, and ornamental Design for a Display Device, of which the following is a specification, reference being had to the accompanying drawing, forming a part thereof.

Figure 1 is a front elevation of a display device embodying my new design,

Figure 2 is an end elevation,
Figure 3 is a top view,
Figure 4 is a vertical section taken along line
A—A of Figure 1, and
Figure 5 is a similar section taken along line
B—B of Figure 1.

I claim:

The ornamental design for a display device, as shown.

C. T. ANDREWS.
